CLARENCE M. CHAPMAN, OF TERRYVILLE, CONNECTICUT.

SOLDERING IMPLEMENT.

Application filed March 25, 1926. Serial No. 97,194.

This invention relates to the construction of electrically heated soldering implements.

The object of the invention is to so design, construct and correlate the parts that 5 a rugged implement is provided, the copper point of which is quickly and efficiently heated by a heating element that, although fragile, is fully protected against damage and is arranged in a position where it may 10 be easily renewed if it burns out.

This object is attained by providing the end of the tubular shank through which the circuit wires are run, with a hollow exteriorly threaded head into which a flanged 15 and slotted end of a metallic core, that is wound with resistance wire, is detachably fastened, and upon which the end of a sleeve that carries the copper point is screwed. The other end of the heating element core 20 extends into the point where it is supported but is free to move longitudinally as the core expands and contracts under temperature changes. The circuit wires are threaded through the tubular shank and led 25 through the slotted end of the metallic core and connected with the resistance wire coiled upon but insulated from the core, after which the sleeve with the point is attached to the head so as to protect the 30 removable heating unit.

In the accompanying drawings Fig. 1 shows a section of the assembled heating unit and the protecting sleeve and point, with the point detachably secured to the 35 sleeve. Fig. 2 is a similar section with the point integral with the protecting sleeve. Fig. 3 is a transverse section on the plane indicated by the dotted line 3-3 on Fig. 2.

The shank 1 of the implement is a length 40 of metallic tube. Securely fastened on the end of the shank is a head 2 with a socket 3. The metallic core 4 of the heating element has a flange 40 at one end and a flange 41 at the other end. The flange 40 of the core 45 is fitted in the socket in the head and retained by screws 5. A slot 6 is made across the flanged end of the metallic core that is set in the head. The resistance wire 7, suitably insulated, is coiled about the metallic 50 core, in one or two layers, and the ends of the circuit wires 8 that are threaded through the tubular shank are led, one each side, through the slot in the embedded end of the core and are connected with the ends of the 55 resistance wire that is coiled upon the core.

A metallic sleeve 9 is threaded upon the head so as to protect the heating unit and provide a suitable mass of heat conducting metal. The copper point 10 may be attached to this sleeve by threading its end 60 and screwing it into the threaded end of the sleeve, as illustrated in Fig. 1, or the sleeve and point may be made integral, as illustrated in Fig. 2. If the point is detachable it may be removed when worn out 65 or injured and another substituted, or a point of a different size may be applied.

The point is socketed and the flange 41 at the free end of the core lies within this socket and is supported by the wall thereof 70 so it retains the heating element in position but is free to move longitudinally as it changes length under expansion and contraction.

With the construction illustrated the heating unit is located close to the operating end of the implement and this heating unit is easily applied when the parts are originally assembled or readily removed and another substituted in case it should burn out. It 75 is convenient to lead the wires from the core through the slots to the tubular shank. The heating unit is thoroughly protected by the sleeve and point. By making the core for the heating unit of metal a rigid structure 80 is produced and one in which the core contributes or assists in absorbing heat from the resistance wire and conducting it to the sleeve and point. Thus the implement heats 85 quickly and with a minimum expenditure of 90 energy.

The invention claimed is:—

1. The combination in an electrical soldering implement having a tubular shank with a socketed head, a sleeve attached to the 95 head and a point attached to the sleeve, of a solid metallic heating element core having an integral flange at each end with a resistance wire wound about said core between the flanges, one of said flanges being entered 100 into the socket of and attached to said head, and the other of said flanges extending into contact with but free to move within the point for supporting that end of the core and transmitting heat to the point without 105 interfering with the lengthwise expansion or contraction of the core.

2. The combination in an electrical soldering implement having a tubular shank with a socketed head, a sleeve attached to the 110

head and a point attached to the sleeve, of a heating element core having an integral flange at each end with a resistance wire wound about said core between the flanges, 5 one of said flanges being slotted to the edge of the core and set into and fastened to the socket of said head, and the other of said flanges extending into contact with but free to move within the point for supporting that 10 end of the core and transmitting heat to the point without interfering with the lengthwise expansion or contraction of the core.

3. The combination in an electrical soldering implement having a tubular shank with 15 a socketed head, a sleeve attached to the head and a point attached to the sleeve, of a solid metallic heating element core having a flange at each end with a resistance wire wound about said core between the flanges, 20 one of said flanges being slotted to the edge of the core and fitted into the socket of said head, and the other of said flanges extending into contact with but free to move within the point to transmit heat thereto, and 25 screws extending through the head and threaded into the slotted end of the core.

4. The combination in an electrical soldering implement having a tubular shank with a socketed head, a sleeve attached to the head and a point attached to the sleeve, of a solid metallic heating element core having a flange at each end with a resistance wire wound about said core between the flanges, 30 one of said flanges being slotted to the edge of the core and set into the socket of said head, and the other of said flanges extending into and freely supported within the point, and screws extending through the head and threaded into the slotted end of the 35

core, said screws being concealed by the end 40 of said sleeve that connects the head and the point.

5. The combination in an electrical soldering implement having a tubular shank with a head, and a point connected with the head, 45 of a solid metallic heating element core having an integral flange at each end with a resistance wire wound about said core between the flanges, one of said flanges being slotted and the slotted end fitted into and 50 detachably secured to said head, and the other of said flanges extending into contact with and freely supported by the point.

6. The combination in an electrical soldering implement having a tubular shank with 55 a socketed head, a sleeve attached to the head and a point attached to the sleeve, of a heating element core having a flange at each end with a resistance wire wound about said core between the flanges, one of said flanges 60 being set into said head, said flange being slotted for the passage of the resistance wire and to allow it to yield under expansion and contraction, and the other of said flanges extending into and freely supported within the 65 point.

7. The combination in an electrical soldering implement having a tubular shank with a head, a sleeve attached to the head and a point attached to the sleeve, of a solid metallic heating element core with a resistance wire wound about said core, one end of said core being slotted and set into a socket in 70 said head, and the other end of said core extending into contact with and freely supported by the point.

CLARENCE M. CHAPMAN.
